STRIP HOLDER

Pauline S. Eckman, San Francisco, Calif.

Application July 2, 1940, Serial No. 343,629

1 Claim. (Cl. 206—72)

This invention relates to equipment for use by dentists.

As is well known, dentists are almost constantly using polishing strips of abrasive material. These strips minutely vary in abrasive qualities from very fine to quite coarse, and all of them must be readily available to the dentist for the immediate selection of the strip or strips that the particular use requires.

It is the object of my invention to provide a holder for such strips which will maintain the strips segregated as to abrasive qualities in a manner making all of the various strips readily available to enable rapid selection thereof without excess handling.

One form which the invention may assume is exemplified in the following description and illustrated by way of example in the accompanying drawing, in which:

Fig. 1 is a perspective view of a strip holder embodying the preferred form of my invention.

Fig. 2 is a front elevation of the same.

Fig. 3 is an end view thereof.

Referring more particularly to the accompanying drawing, I show a strip holder for use by dentists for making readily available abrasive strips which are frequently used by dentists in their practice. These strips are commercial products and are provided in various widths and in various lengths and are provided in varying degrees of abrasive qualities from quite fine to quite coarse, so that the dentist may select for use the strip having the abrasive quality proper for the particular operation at hand. These strips are used in considerable quantities and all of them must be available for immediate selection by the dentist in order that time may be saved.

The present device contemplates the provision of means to make a number of the strips of each abrasive quality quickly available and readily accessible to the dentist for use, and it comprises a base 10 preferably of sufficient dimensions that it will enable strips to be removed from the mechanism carried thereby as will be described.

This mechanism comprises a plurality of longitudinally disposed and parallel shafts 12 which are spaced equal distances apart in a position overlying the base 10 and extending longitudinally thereof. These shafts are suitably journalled in bearing members 11 secured to the base 10, as illustrated. One outer end of each shaft is bent in the form of a crank 14 and all of these cranks are connected together by a connecting rod 15 so that reciprocation of this rod will par-

tially revolve the shafts 12. A keeper 16 is carried by the connecting rod 15 to engage keeper openings 17 and 18 formed in the base. When the keeper is in the opening 17, the shafts are maintained in one position, and when the keeper is removed therefrom and engaged with the keeper opening 18, the shafts are maintained in a second position.

Secured on each shaft 12 is a pair of clips 19 preferably formed of sheet metal with an upraised tang 20 punched from the surface thereof, as illustrated in Figs. 1 and 3, forming a sort of a U-shaped spring clip for reception of the abrasive strips, as illustrated in Fig. 2.

When the keeper 16 is engaged with the opening 17, the clips 19 are held in an upraised position so that the strips carried by the clips are readily available for removal and use. When the keeper 16 is engaged with the keeper opening 18, the clips lie flatwise on top of the base, as indicated by dotted lines in Fig. 3 of the drawing. In this position they will be disposed in an unobstructing fashion so that the device may be stored away when not in use.

In practice, I prefer that the strips be arranged on the pairs of clips 19 in the order of their degrees of abrasive quality. However, this is not essential.

I am fully aware that various other mechanical means can be employed for operating the strip holding clips herein discussed, and I, therefore, do not limit myself to this precise arrangement.

From the foregoing it is obvious that I have provided a very efficient device for holding abrasive strips which will maintain the strips segregated as to abrasive qualities and in a manner making readily available all of the strips for use. I have found that the device is a considerable time saver and enables more efficient selection and handling of the abrasive strips.

While I have shown the preferred form of my invention, it is to be understood that various changes may be made in its construction by those skilled in the art without departing from the spirit of the invention as defined in the appended claim.

Having thus described my invention, what I claim and desire to secure by Letters Patent is:

50 A device of the character described comprising a flat base, a plurality of shafts arranged in parallelism to each other at spaced distances apart and parallel to the adjacent face of the base and positioned a slight distance above the face of the base, said shafts being rotatably supported at

their ends on the base, a pair of strip holding clips fixed on each shaft adjacent the ends thereof and extending radially from said shafts, a crank at the end of each shaft, connecting means connecting said cranks in parallelism and capable of simultaneously operating all of said shafts to dispose said strip holding clips either in an

upraised position relative to the face of the base or in a flatwise position relative to and closely adjacent to the face of the base, and keeper means for maintaining the connecting means in an adjusted position.
